MULTIPLE ELECTRIC SECURITY JACK
Simon Barisin, 2671 Tucuman St., Olivos,
Buenos Aires, Argentina
Filed July 9, 1959, Ser. No. 825,937
3 Claims. (Cl. 339—36)

The present invention refers to a multiple safety outlet, to be used affixed to any given surface, in order to receive when required, a plurality of electric plugs, thus avoiding unnecessary massiveness, as it generally occurs with systems known at present.

One of the advantageous applications of this invention is its use in bedrooms, particularly in back of heavy pieces of furniture, where often several electric appliances are permanently connected.

Due to its characteristics, the safety outlet can be furnished with any convenient number of receptive pairs of sockets which can be adapted to receive cylindrical as well as flat-shaped prongs, or whatever combination of these two well known systems is desired.

For safety's sake, each pair of sockets carries an internal covering plate, which operates only when a locking means, which is part of the mechanism, is turned into a dead position.

Such locking means in its operative position prevents the sliding of the internal covering plate of any given receptive pair of sockets, and the locking means is so constructed so that it can be operated even though one or more plugs are in use.

The execution of this invention will be carried out in any proper sizes, materials and forms considered more appropriate for aforesaid purposes.

In all figures of the drawing same reference numerals indicate equal or corresponding parts. For the purpose of illustrating the invention, there are shown in the accompanying drawings forms thereof which are at present preferred, although it is to be understood that the various instrumentalities of which the invention consists can be variously arranged and organized and that the invention is not limited to the precise arrangements and organizations of the instrumentalities as herein shown and described.

Referring to the drawings in which like reference characters refer to like parts:

FIGURE 1 is a perspective view of a preferred form of construction of the unit according with the present invention.

FIGURE 2 is a perspective rear view of the unit of FIGURE 1, partially broken in order to show the interior of the unit.

FIGURE 3 is a perspective view of the covering plate locking means.

FIGURE 4 is a cross section of the unit, showing the way how the locking means operates upon the covering plate.

Referring to the accompanying drawings the electric outlet of the present invention comprises an external case formed by two halves 1, 2 conveniently joined together, having each a prismatic rectangular shape, and each provided on one of the edges with cutouts 3, 4 forming circular or rectangular openings receptive of prongs 5, 6 of an electric plug 7.

Under each pair of openings a sliding or movable plate 8 is disposed, showing identical and corresponding perforations, which when displaced by the operating frontal knob 9 allows the introduction of prongs towards inner contacts 10, 11.

A spring 12 is connected to each sliding plate, forcing the same to its closing position.

The aforesaid plates are formed on one of the edges

2

with cutouts 13, 14 which are adapted to alternatively lodge the projection 15, of a bar 16, turnable by means of an end knob 17, which projects out of the external case at either end, as preferred.

5 When it is desired to prevent any movement of the covering plates, it will be sufficient therefore to turn the knob 17 at the end of the external case, which movement will cause the corresponding projection 15 of the bar 16 to extend into the respective cutout 13, thus eliminating 10 possible displacements of the plates.

The casing 1, 2 may be fastened by screws 19, shown in cross section in FIG. 2 to a wall and the bar 16 may be formed with bends or crank portions 18 in order not to interfere with the screws 19.

15 Such tie can be obtained even though when one or more sections of the electric outlet are used.

The present invention may be embodied in other specific forms without departing from the essential attributes thereof, and it is therefore desired that the present embodiments be considered in all respects as illustrative and not restrictive, reference being had to the appended claims rather than to the foregoing description to indicate the scope of the invention.

Having described my invention, I claim:

25 1. A safety electrical outlet comprising, in combination, an elongated housing formed in a wall thereof with a plurality of pairs of apertures respectively adapted for receiving the prongs of electrical plugs; a plate for each pair of apertures slidably arranged in said housing adjacent 30 said wall and movable between an open position permitting insertion of the prongs of an electrical plug through the respective pair of apertures and a closed position preventing insertion of such prongs through said pair of apertures; spring means operatively connected to 35 each of said plates and tending to move the same to said closed position thereof; manually operable means connected to each plate and extending to the exterior of the housing for moving said plate against the pressure of said spring means from said closed to said open position so 40 that prongs of a plug may be inserted through the respective pair of apertures; and a single locking means cooperating with all of said plates for locking the plates which are moved to the open position in said open position while locking at the same time the plates which are left in the 45 closed position in said closed position.

2. A safety electrical outlet comprising, in combination, an elongated housing formed in a wall thereof with a plurality of pairs of apertures respectively adapted for receiving the prongs of electrical plugs; a plate for each 50 pair of apertures arranged in said housing adjacent said wall, each of said plates being formed with a pair of cutouts and being movable in longitudinal direction of said housing a preselected distance between an open position in which said cut-outs are aligned with the corresponding 55 pair of apertures thus permitting insertion of the prongs of an electrical plug through the respective pair of apertures and said cut-outs and a closed position in which said pair of cut-outs are out of alignment with the corresponding pair of apertures, thus preventing insertion of said 60 prongs; spring means operatively connected to each of said plates and tending to move the same to said closed position thereof; manually operable means connected to each plate and extending to the exterior of the housing for moving said plate against the pressure of said spring 65 means from said closed to said open position so that the prongs of a plug may be inserted through the respective pair of apertures; and a single locking means cooperating with all of said plates for locking the plates which are moved to the open position in said open position while locking at the same time the plates which are left in the 70 closed position in said closed position.

3. A safety electrical outlet comprising, in combination, an elongated housing formed in a wall thereof with a plurality of pairs of apertures respectively adapted for receiving the prongs of electrical plugs; a plate for each pair of apertures arranged in said housing adjacent said wall, each of said plates being formed with a pair of cut-outs and being movable in longitudinal direction of said housing a preselected distance between an open position in which said cut-outs are aligned with the corresponding pair of apertures thus permitting insertion of the prongs of an electrical plug through the respective pair of apertures and said cut-outs and a closed position in which said pair of cut-outs are out of alignment with the corresponding pair of apertures, thus preventing insertion of said prongs, each of said plates being further formed at an edge thereof extending in longitudinal direction of said housing with a pair of notches extending from said edge substantially normal thereto into said plates and being spaced from each other said preselected distance; spring means operatively connected to each of said plates and tending to move the same to said closed position thereof; manually operable means connected to each plate and extending to the exterior of the housing for moving said plate against the pressure of said spring means from said closed to said open position so that the prongs of a plug may be inserted through the respective pair of apertures; and a single locking means cooperating with all of said plates for locking the plates which are moved to the open

25

position in said open position while locking at the same time the plates which are left in the closed position in said closed position, said locking means comprising an elongated rod extending in longitudinal direction of said housing and being mounted therein turnably about its axis, and a plurality of prongs fixed to said rod extending in transverse direction of said axis and being spaced from each other so that consecutive prongs are respectively aligned with one notch of consecutive plates when said plates are in said closed position and so that said prongs are aligned with the other notch of the respective plate when said plate is moved in said preselected distance from said closed to said open position, said rod being turnable from a locking position in which said prongs are located in said notches and an unlocking position in which said prongs are out of said notches, whereby the plates moved from said closed to said open position thereof may be locked by said prongs in said open position while the remaining plates are at the same time locked in the closed position thereof when said rod is turned from said unlocking position to said locking position.
